UNITED STATES PATENT OFFICE.

GODFREY KNOOS, JR., OF PHILADELPHIA, PENNSYLVANIA.

PLAYING-CARDS.

1,314,522.

Specification of Letters Patent. Patented Sept. 2, 1919.

Application filed December 16, 1918. Serial No. 266,960.

To all whom it may concern:

Be it known that I, GODFREY KNOOS, Jr., a citizen of the United States, residing at Philadelphia, in the county of Philadelphia and State of Pennsylvania, have invented 5 certain new and useful Improvements in Playing-Cards, of which the following is a specification.

This invention relates to card games, and 10 an object of the invention is to provide a card game of such simplicity that it may be readily understood, without considerable explanation as to the object in view and the manner of playing; one which would be interesting and would promote good will 15 among the players, tending to relieve strain which often is among guests at parties or analogous gatherings, who are not well acquainted one with another.

20 More specifically, the invention comprehends the provision of a set of playing cards, comprising two sets of an equal number of cards, one set differing from the other in that one has uneven numbers, together with 25 questions and answers appropriate for male members or players, and the other set has even numbers and questions and answers appropriate for female players of the game.

Other objects of the invention will appear 30 in the following detailed description, taken in connection with the accompanying drawing, forming a part of this specification and in which drawing:

Figure 1 illustrates the first card of one 35 set, namely the set bearing questions and answers appropriate for male members.

Fig. 2 illustrates the first card of the set bearing questions and answers appropriate for female members.

40 Fig. 3 illustrates a subsequent card of the set bearing questions and answers appropriate for male members, and

Fig. 4 illustrates a subsequent card of the set bearing questions and answers appropriate 45 for female members.

Referring more particularly to the drawings, A indicates the first card of one set of cards of the set, and A² indicates the second or subsequent card of the said set. These 50 cards A and A², bear suitable indicia indicated at B to determine the set to which they belong and also to determine succession in which the cards are brought into place. In the drawings, this indicia is in the form of 55 uneven numbers, while in the cards C and C², of the set bearing answers and questions

suitable for female members, the indicia B is in the form of even numbers, which numbers determine the sets to which the cards belong as well as determining the succession in 60 which the cards are brought into play.

The cards of the set to which the cards A and A² relate or belong, bear answers indicated at D to questions indicated at E on the cards of the set to which the cards C and C² 65 belong, the card number 3 bearing the answer to the question D on the preceding card, or upon the card bearing the number 2, while this card C which bears the number 2 carries the answer D to the question E 70 which is carried by the card A or the card bearing the preceding number, such as 1. This succession of questions and answers is carried out through the entire deck of cards, and the answer D upon the first card of the 75 set, namely the card A is appropriate to the question upon the last card of the deck, thereby completing a rotation of questions and answers throughout the entire deck of cards. These questions and answers may be 80 of any desired nature, such as educational questions, but it is preferred to make them of such nature as to promote good feeling and fellowship among the players and tend to relieve any strain, shyness or bashfulness 85 which may exist among guests at a party or analogous gathering.

In playing the game, the deck of cards is dealt to the players, the cards of the set bearing the uneven numbers being dealt to the 90 male players while the cards bearing the even numbers are dealt to the female players. After all of the cards have been dealt, the person having the card bearing the number 1 or the first number of the deck reads 95 the question upon the card, and the female player having the card bearing the number 2 or the first number after that from which the question was read reads the answer from the top of the card and in turn reads the 100 question upon the card which is answered by the answer of the card bearing the next uneven number. In this manner, the questions and answers are read from all of the cards and the answer upon the first card is to the 105 question upon the last card of the deck.

From the foregoing description, taken in connection with the drawings, it will be apparent that a card game has been provided which is extremely simple and may be readily understood, eliminating the necessity of extensive instructions as to the manner of

playing the game and the object aimed at by the playing of the game and one which will promote good will and acquaintance-ship among the players.

5. Changes in details may be made without departing from the spirit of the invention, but;

I claim:

1. A deck of playing cards comprising 10 two sets of cards, each card of each set bearing a question and an answer, the answer of any given card of one set being related to a predetermined question of a card of the other set, said cards further bearing set-determining indicia.
2. A deck of playing cards comprising two sets of cards, each card of each set bearing a question and an answer, the answer of any given card of one set being 15 related to the predetermined question on a card of the other set, said cards further bearing set-determining indicia, said set-determining indicia also indicating the succession of the cards during playing.
3. A deck of playing cards comprising 20 sets of cards, certain of the cards bearing questions appropriated for male players, and certain others bearing questions appropriate for female members, said cards also bearing answers, the answer of any given card of one set being related to a predetermined question on a card of the other set.
4. A deck of playing cards comprising 25 sets of cards, certain of the cards bearing questions appropriate for male players, and certain others bearing questions appropriate for female members, said cards also bearing

ing answers, the answer of any given card of one set being related to a predetermined question on a card of the other set, said 40 cards bearing set-determining indicia indicating the succession of the cards during playing.

5. A deck of playing cards comprising two sets of cards, the cards of one set bearing 45 questions appropriate for male players, and the cards of the other set bearing questions appropriate for female players, the cards of said sets also bearing answers, the answer of any given card of one set being 50 related to a predetermined question on a card of the other set.

6. A deck of cards comprising two sets of an equal number of cards, the cards of one set bearing questions appropriate for 55 male players, and the cards of the other set bearing questions appropriate for female players, said cards also bearing answers, the answer of any given card of one set being related to a predetermined question 60 on a card of the other set, said cards also bearing set-determining indicia indicating the succession of the cards during playing.

7. A deck of playing cards comprising two sets of an equal number of cards, the 65 cards of one set bearing questions appropriate for male players, and uneven numbers, and the cards of the other set bearing questions appropriate for female players and even numbers, said cards also bearing 70 answers, the answer of any given card of one set being related to a predetermined question on a card of the other set.
